UNITED STATES PATENT OFFICE.

WILLIAM A. KEAHEY, OF GARNETT, ARKANSAS.

PLOW.

SPECIFICATION forming part of Letters Patent No. 468,179, dated February 2, 1892.

Application filed May 16, 1891. Serial No. 392,993. (No model.)

To all whom it may concern:

Be it known that I, WILLIAM A. KEAHEY, a citizen of the United States, and a resident of Garnett, in the county of Lincoln and State of 5 Arkansas, have invented certain new and useful Improvements in Plows; and I do hereby declare that the following is a full, clear, and exact description of the invention, which will enable others skilled in the art to which it 10 appertains to make and use the same, reference being had to the accompanying drawings, which form a part of this specification.

My invention relates to improvements in what are known as "double-shovel plows," the 15 object being to provide a simple and economical construction of the same, whereby the sheths carrying the shovels may be laterally adjusted so as to vary the distance between the furrows turned thereby.

20 The invention consists in the novel construction and combinations of parts herein-after fully described and claimed.

In the accompanying drawings, Figure 1 is a perspective view of a plow constructed in 25 accordance with my invention. Fig. 2 is a detail view of the device for adjustably connecting the sheths, and Fig. 3 is a sectional view of the sheth-adjusting devices.

In the said drawings the reference-numeral 30 1 designates the plow-beam, which may be provided with an ordinary colter. To the rear end of this beam is connected the front ends of the sheths 3, made of spring metal and having their rear ends curved down- 35 wardly and provided with the shovels 4.

The numerals 5 5 designate the handles, having their front ends connected with the sheths by means of clips 6 6. Intermediate of their ends these handles are connected 40 with the curved portions of the sheths by means of arms 7 7, secured to the latter at their lower ends and having their upper ends provided with a series of holes or apertures 8 8, through which the handles pass bolts 45 or pins 9 9, by which they are adjustably secured thereto, so as to vary the height of the shovels.

Intermediate of the front ends of the handles and the arms 7 7 is an adjustable device 50 for laterally adjusting the distance of the sheths from each other. This device consists of two metallic plates 10 10, the outer ends of which are bent downwardly and then in-

wardly, forming clamps 12 12, which embrace the sheths. These plates overlap each other 55 and are provided with a series of holes or apertures 13 13, through which passes a headed bolt 14, provided with a binding-nut 15, provided with an operating-handle by which they are held together, being also provided 60 with a clamp 16, consisting of a metallic loop, which embraces the same and also aids in holding them. One of the plates 10 has its end reduced and turned upward and is inserted in one of the holes of the other plate, 65 thereby preventing the said plates twisting one upon the other should by any possible means the clip or clamp 16 slide past the end of the lower plate. The plates are also provided with screw-bolts 17 17, which pass there- 70 through and through the inwardly-bent ends, whereby they are securely attached to the sheths.

The operation will be readily understood. When it is desired to increase the distance 75 between the furrow formed by the shovels, the bolt 14 is loosened by removing the nut 15 by means of a wrench 18, allowing said bolt to be withdrawn. The sheths are then spread apart, and when the required distance has 80 been reached the bolt is again inserted in the apertures in the plate and secured in place by the binding-nut.

Having thus described my invention, what 85 F claim is—

In a plow, the combination, with the beam, the spring-sheths secured thereto and provided with shovels, the handles secured to said sheths by the clips, and the adjustable arms, of the adjustable plates having down- 90 wardly and inwardly turned outer ends overlapping each other and provided with a series of registering apertures, the inner end of one of said plates being provided with an upturned lip to project into one of the apertures in the other plate, the bolts and nuts for securing said plates together, and the bolts and nuts for securing said plates to the sheths, substantially as described.

In testimony that I claim the foregoing as 100 my own I have hereunto affixed my signature in presence of two witnesses.

WILLIAM A. KEAHEY.
